MACHINE FOR FORMING GEAR GUARDS

Application filed January 14, 1930. Serial No. 420,785.

This invention relates to improvements in machines for forming sheet metal, particularly gear guards, and it is the general object of the invention to provide a machine capable of forming gear guards and the like from sheet metal so as to give them a variety of forms.

In my co-pending application Ser. No. 407,838 I have described a gear guard formed of sheet metal wherein one side of a piece of angle material is corrugated or otherwise deformed so as to cause curvature in the other side of the material. This is conveniently accomplished by providing a strip of material having two portions bent at right angles to each other and providing one of said portions with tapered corrugations so that one edge of the strip is materially shortened while the center line of fold retains its original length. In this way curvature of the other portion is produced and this curvature can be varied by the amount of taper of the corrugations. It is an important object of my invention to provide a pattern or control member to vary the angular relation of a pair of corrugating rolls so as to produce a variety of radii of curvature as well as uncurved parts.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a vertical section through the operating parts of a machine made according to my present invention;

Fig. 2 is a vertical section on line 2—2 of Fig. 1;

Fig. 3 is an end elevation taken in the direction of arrow 3, Fig. 1;

Fig. 4 is a perspective view of a gear guard such as can be made by the particular form of controller cam shown in Fig. 2;

Fig. 5 is a diagrammatic view of the guard showing the straight and variously curved portions; and

Fig. 6 is a plan of a pattern or control mem-

ber capable of producing a curve of constant radius.

The machine has a base plate 10 provided with an upright standard 11 which supports a lower corrugating roller 12 formed with corrugating teeth 13. The roller may be formed as a part of shaft 14 which extends through the standard and has keyed to the right-hand thereof, as viewed in Fig. 1, a small driven gear 15. The latter meshes with a motor gear 16 shown in Fig. 3 driven by a motor M secured to the base plate 10.

The upright 11 has a narrower upper portion 17 from which extends a horizontal brace 18. In said portion 17 I secure a stud 19 on which is mounted a relatively large gear 20 meshing with gear 15 and keyed to a pinion 21. The gear and pinion 20 and 21, respectively, rotate around the stud 19.

A relatively large controller gear 22 meshes with the pinion 21 and is rotatable about the shaft 14, being driven at a slower rate of speed than the latter by means of the reduction gearing described. The shaft 14 and stud 19 may be surrounded by bushings to provide improved bearings if desired.

The controller gear 22 has that face thereof adjacent the upright 11 formed with a pocket 23 defined in part by an annulus 24. Located within the pocket 23 is a controller cam 25 held against angular movement with respect to the controller gear by means of keys 26. The cam shown in Fig. 2 has an internal surface which has an area 27 of relatively large radius, another area 28 of smaller radius and a third area 29 of still smaller radius. As shown herein the cam surfaces 28 and 29 are connected by an area 30 which may be of the same radius as the first described area 27.

As seen in Figs. 1 and 3 the brace 18 has mounted thereon a yoke 31 held in position by a screw 32 and provided with a pair of spaced hooked-shaped bearings 33. A bearing member 34 has a central portion 35 of relatively large diameter to be received by the downwardly facing concave surface 36 formed on the brace 18. Said portion 35 is provided with a bore 37 through which extends the outer end 38 of a shaft 39. The

central portion 35 may be slabbed as at 40 to engage a flange 41 preferably formed integral with the shaft 39.

Freely rotatable on the shaft 39 is a second corrugated roller 42 having teeth 43 corresponding to the teeth 13 of the first described roller. The second roller is limited as to movement to the left as viewed in Fig. 1 by the shoulder 41 and likewise limited as to movement to the right by an adjustable collar 44 secured to the shaft 39.

The right-hand end of the shaft 39 as shown in Fig. 1 has rotatably mounted thereon a crowned roller 45 positioned for engagement with the internal cam surfaces heretofore described. A comparatively heavy compression spring 46 is interposed between the under side of the shaft 39 and the upright portion 11, being received by a pocket 47 formed in the latter. The purpose of said spring is to hold the roller 45 against the controller cam. The reduced portion 17 is provided with a vertical slot 48 which confines the spring 46 and also permits up and down motion of the shaft 39.

The machine herein described is formed for cooperation with a strip of sheet metal which has two portions thereof 50 and 51, respectively, disposed at right angles to each other, the material being so formed prior to presentation to the rollers.

In operation an angle strip of sheet material will have one end of the horizontal portion 51 thereof presented to the corrugating teeth 13 and 43, respectively. Assuming that the gearing is such as to cause the cam face to move in the direction of arrow 52, Fig. 2, with the parts in the position shown in the latter figure, the rollers 12 and 42 will have their axes substantially parallel during the time that the cam is moving from the point designated at 53 in Fig. 2 until it reaches point 54 near area 28. During this rotation the rollers will have sufficient contact with the stock or horizontal portion 51 to move the latter between them by a feeding action which does not materially deform the said horizontal portion 51. As soon as the point 54 reaches the roller, however, the latter will move downwardly so as to produce an angle between the shafts 14 and 39. The parts are so proportioned that there will be very little if any distance between the left-hand ends of the teeth 13 and 43, but there will be an appreciable lessening of the distance between the right-hand end of the teeth and as the machine continues to operate the portion 51 of the material being acted upon will be given tapering corrugations of a rather shallow form. Continued rotation of the control cam will bring the point 55 thereof at the end of area 28 into engagement with the roller 45 and the spring 46 will reestablish the parallel relation of the shafts 14 and 39. During the time thereafter that the roll 45

is in engagement with the surface 30 of the control cam the portion 51 will be fed through without substantial deformation. As the roller reaches the point 56 in the cam at the beginning of area 29 it will be given a downward motion greater than that which is received previously and will be held in this position during the short time that the roller is in engagement with the surface 29. As the end of the said surface 29 arrives under the roller the latter will again move into engagement with the surface 27 to accomplish a simple feeding movement of the horizontal portion 51 without forming corrugations.

In Fig. 5 I have given a diagrammatic view of the portion 51 of the guard, wherein the portion A corresponds to a part of the surface 27, the portion B of relatively large radius of curvature corresponds to surface 28, straight portion C corresponds to the surface 30, portion D corresponds to the surface 29 which produces a relatively small radius of curvature, and straight portion E corresponds to the remainder of the surface 27. It is to be understood that the form of the cam may be varied to produce different contours, and it is not necessary that the length of the portions A and E be strictly proportional to the length of the surface 27. By selecting the time of feeding the material with respect to the location of the roller 45 along the surface 27 the operator of the machine can vary the lengths of the portions A and E.

It will be understood that if it is desired to produce a guard section of but one radius of curvature the cam will take the form of a simple ring with an internal surface 70 as shown in Fig. 6 concentric with the shaft 14. The desired result is attained by maintaining the rollers 12 and 42 in the same angular relation throughout the guard forming operation. It is to be understood that the two forms of guard set forth herein are merely exemplary of a variety which can be produced by my present invention and that the only part which needs replacing is the controller cam.

While I have shown the invention as operating on an angle section, yet I am not limited to this form, as a plane strip of material can be given various curves to alter its contour.

From the foregoing it will be seen that I have provided a simple form of mechanism for deforming one side of a strip of sheet stock more than the other side so as to produce straight and variably curved portions. It will further be seen that the same machine may be employed to produce various shapes of guards merely by changing the controller cam. It will also be seen that when straight gear sections are desired the rollers 12 and 42 may be so related as to effect a simple

feeding of the material without forming corrugations.

Having thus described my invention it will be seen that changes and modifications may be made therein by those skilled in the art without departing from the spirit and scope of the invention and I do not wish to be limited to the details herein disclosed, but what I claim is:

1. In a machine for corrugating sheet material, a pair of corrugating rollers movable one with respect to the other and capable of having their axes substantially parallel, a pattern surface, and means operatively interposed between one of said rollers and the pattern surface to effect a change in the angular relation between the axes of the corrugating rollers to vary the character of corrugation produced by said rollers in the material. 10
2. In a machine for corrugating sheet material, a pair of corrugating rollers capable of assuming a plurality of angular positions with respect to each other, a pattern surface, means acted upon by the pattern surface to vary the angular relation between the corrugating rollers, and means to cause the pattern surface and rollers to move in timed relation. 20
3. In a machine for corrugating sheet material, a pair of corrugation forming rollers to co-act in producing a corrugation in sheet material, said rollers being capable of assuming a plurality of angular positions with respect to each other, a movable controller surface, geared connections between the controller surface and the rollers to cause said surface and rollers to move in timed relation, and means under control of the controller and movable thereby as the controller surface moves to vary the angular relation between the corrugation forming rollers to produce corrugations of different characters to be formed in the sheet material. 30
4. In a machine for corrugating sheet material, a pair of corrugating rollers capable of having their axes parallel and also disposed at angles with respect to each other, a pattern surface movable in timed relation with the rollers, and connections between the surface and the rollers controlled by the surface and effective to cause the axes of said rollers to assume a parallel relation, or any angular relation within a limited range depending upon the pattern surface, to cause corrugations of differing characters to be formed in the sheet material. 40
5. In a machine for corrugating sheet material, a corrugating roll movable about a stationary axis, a second corrugating roll to cooperate with the first roll and movable about an axis which may assume any one of a plurality of angular positions with respect to the axis of the first roll, a pattern surface, and means operatively connecting the surface

with the movable roller to effect differing angular relationships between the axes to effect changes in the character of corrugations produced in the material.

6. In a machine for corrugating sheet material, a pair of corrugating rollers capable of co-acting and operating upon a strip of sheet material to form corrugations therein, and a pattern surface movable in timed relation with the rollers and operatively connected thereto to vary the character of corrugations formed in the sheet material. 70

7. In a machine for corrugating sheet material, a pair of corrugation forming rollers capable of co-acting with a sheet of material 80 to feed the same between the rollers and also form therein corrugations tapering in differing degrees, and a pattern surface movable in timed relation with the rollers to cause the latter to produce corrugations of varying degrees of taper in the sheet material. 85

8. In a machine for corrugating sheet material, a pair of feeding corrugation forming rollers to act upon a strip of sheet material to form corrugations therein and also advance 90 said strip between the rollers, and means to vary the degree of taper formed in the strip of sheet material by the rollers, said means acting in timed relation with the feeding of the strip of sheet material. 95

9. In a machine for corrugating sheet material, a pair of corrugating rollers to form tapered corrugations in the sheet material, a member moving in timed relation with the rollers, and a removable pattern surface normally fixed to the member and moving therewith and operatively connected to the rollers to vary the degree of taper caused by said rollers in the sheet material. 100

In testimony whereof I have hereunto affixed my signature.

WALTER H. WAKEFIELD.
